UNITED STATES PATENT OFFICE.

HARRY A. HOKE, OF ALTOONA, PENNSYLVANIA.

RAILWAY-VEHICLE COUPLING.

1,216,692.

Specification of Letters Patent. Patented Feb. 20, 1917.

Application filed September 7, 1916. Serial No. 118,797.

To all whom it may concern:

Be it known that I, HARRY A. HOKE, a citizen of the United States of America, and a resident of Altoona, in the county of 5 Blair and State of Pennsylvania, have invented a certain new and useful Improvement in Railway-Vehicle Couplings, of which the following is a true and exact description, reference being had to the accompanying drawings, which form a part thereof.

The general object of my invention is to provide an improved draft, or load transmitting connection between railway vehicles 15 and particularly between a railway locomotive and its tender. A more specific object of my invention is to provide a locomotive and tender draft connection which will possess the strength and security required by standard railway practice and 20 governmental regulations, and which will be free from certain practical defects inherent in the constructions now in general use.

In the locomotive and tender connections 25 now in general use the load is normally transmitted through a draw bar pivotally connected at one end to the locomotive by a vertical drawbar pin carried by the locomotive, and pivotally connected at the other 30 end to the tender by a vertical drawbar pin carried by the tender. Standard railway practice and governmental regulations require this bar to be strong enough to carry much more than the estimated maximum 35 load. It is also required that a supplemental "safety" connection be provided between the locomotive and tender which shall not be under tension but idle, so long as the draw bar is operative, but in case of fracture 40 of the latter will form a load transmitting connection between the locomotive and tender of suitable strength.

In practice, this safety connection is 45 formed by a pair of so called "safety bars" or "safety chains," connected at their opposite ends to the locomotive and tender respectively one at one side and the other bar at the other side of the longitudinal vertical central plane of the locomotive and 50 tender. To prevent the safety bars or chains from being put under tension while the drawbar is intact, slack must be provided, and this slack must be considerable to prevent one or the other of the safety bars or 55 chains from being put under tension in running around curves. In consequence of

this considerable slack and the arrangement of the bars or chains at opposite sides of the longitudinal center line of the locomotive, in case of rupture of the drawbar the whole 60 load is put upon one only of the safety bars or chains when the locomotive is running around a curve, and when the drawbar fails while the locomotive is traveling in a straight line an appreciable movement between the 65 locomotive and tender occurs before the safety bars or chains are put under tension. This results in many cases in subjecting the safety connections to a rupturing shock.

I avoid the difficulties referred to by employing a safety connection having the axes 70 of its pivotal connection with the locomotive and tender approximately or exactly coincident with the axes of the pivotal connections of the drawbar proper to the engine 75 and tender. In the preferred practical embodiment of my invention I provide the foot plate of the engine and the drawbar pocket member of the tender with spaces to receive the ends of a supplemental safety bar lying 80 directly above or below the main drawbar, preferably the latter, and I connect the safety bar to the engine and tender by the same drawbar pins employed to connect the drawbar thereto. To enable this supplementary bar to serve purely as a safety bar, one 85 or both of the openings formed therein to receive the drawbar pins are elongated to provide sufficient slack so that the safety bar will not be put under tension while the 90 drawbar is intact. The slack thus provided for may be small in comparison, however, with that necessary with the safety connections arranged as heretofore at opposite sides of the longitudinal center line of the 95 locomotive and tender, and the amount of this slack is practically the same when the locomotive is running around a curve as when traveling in a straight line.

The various features of novelty which 100 characterize my invention are pointed out with particularity in the claims annexed to and forming a part of this specification. For a better understanding of the invention, however, and the advantages possessed by 105 it, reference should be had to the accompanying drawings and descriptive matter in which I have illustrated and described a preferred embodiment.

Of the drawings:

Figure 1 is a vertical section through a portion of a locomotive and tender the sec-

tion being taken along the longitudinal center line of the locomotive and tender; and

Fig. 2 is an end elevation of a portion of the locomotive shown in Fig. 1 with the drawbar and safety bar in section.

In the drawings, A represents the foot plate of a locomotive and B represents the drawbar pocket member of a locomotive tender. The members A and B are provided with the usual pockets or spaces A' and B', respectively, to receive the opposite ends of the usual drawbar C. The latter is formed at its opposite ends with the usual eyes or openings C' through which pass the vertical drawbar pins D and E received in the usual bushed holes formed in the foot plate A and drawbar pocket member B respectively. F represents the supplemental connection, or safety bar, which has its opposite ends extending into pockets A² and B² formed in the foot plate of the locomotive and the drawbar pocket member of the tender respectively.

The pocket A² in the construction shown immediately beneath the pocket A', and the pocket B² is beneath the pocket B'. The drawbar pins D and E extend through the pockets A² and B² respectively and pass through eyes or apertures F' and F² formed in the opposite ends of the safety bar F.

As shown, the aperture F' is elongated about as much as are the apertures C' in the drawbars C, while the aperture F² in the safety bar is elongated somewhat more so that in the normal operative condition of the drawbar C, the safety bar F is not under tension. The slack provided by the extra elongation of the eye F² should be only sufficient, however, to permit a slight movement of separation between the locomotive and tender before the safety bar F comes into play, in case the drawbar C ruptures.

Advantageously the bushings G for the lower ends of the drawbar pins D and E are provided with inturned flanges G' which fit about reduced lower portions D' and E' respectively of the drawbar pins D and E, and prevent the lower portions of the bodies of the drawbar pins from dropping out of operative relation with the safety bar F in case the drawbar pins are broken where engaged by the drawbar C. D² and E² represent keys passing through the reduced lower ends of the drawbar pins to prevent dis- placement of the latter.

While in accordance with the provisions of the statutes I have illustrated and described the best form of my invention now known to me, it will be apparent to those skilled in the art that changes can be made in the form of the invention without departing from its spirit, and that some features of my invention can be used without a corresponding use of other features of the invention.

Having now described my invention, what I claim as new and desire to secure by Letters Patent, is:—

1. The combination with two railway vehicles to be connected, of a draw bar pivotally connected at its ends thereto, and a supplemental safety connection also pivotally connected at its ends thereto, with the axis of its pivotal connection to each vehicle substantially coincident with the axis of the pivotal connection of the draw bar to said vehicle, the parts being so relatively arranged that the draw bar connection, so long as it is operative, forms the load transmitting connection between said vehicles. 70 75

2. The combination with two railway vehicles to be connected, of a draw bar, draw bar pins pivotally connecting the ends of the draw bar to said vehicles, and a supplemental safety connection connected by said draw bar pins to said vehicles with provision for lost motion whereby said draw bar forms the load transmitting connection between said vehicles so long as the latter are operatively connected by said draw bar. 80

3. The combination with two railway vehicles to be connected, each provided with a vertical draw bar pin and upper, intermediate and lower apertured parts through which said pin passes and which provides 90 bearings for upper, lower and intermediate portions of the pin, and a pair of coupling parts each pivotally connected at its opposite ends to the two draw bar pins, one of said coupling parts being received between 100 the upper and intermediate apertured parts and the other between the intermediate and lower apertured parts of each vehicle, the lower apertured part of each vehicle having provisions engaging the lower portion of 105 the corresponding draw bar pin to prevent downward movement of the pin.

4. The combination with an engine having a foot plate provided with a drawbar pocket and beneath the drawbar pocket with 110 a pocket for receiving the end of a safety bar and formed with aligned passages through the walls of said pockets for a drawbar pin, and a tender having a drawbar pocket member formed with a drawbar 115 pocket proper and beneath the latter with a pocket to receive the end of a safety bar, and formed also with aligned passages through the walls of said pockets for a drawbar pin, of a drawbar having its ends received in the 120 drawbar pockets of said foot plate and member and having apertures in its ends to receive the drawbar pins, and a safety bar having its ends received in the lower pockets of said foot plate and drawbar pocket member, and having apertures in its ends to receive said drawbar pins, and drawbar pins mounted in said passages and passing through said apertures, the apertures in said bars being so relatively arranged as to pre- 125 130 135

vent the safety bar from being put under tension so long as the drawbar forms an operative connection between the engine and tender.

5. The combination with an engine having a foot plate provided with a drawbar pocket and beneath the drawbar pocket with a pocket for receiving the end of a safety bar and formed with alined passages 10 through the walls of said pockets for a drawbar pin, and a tender having a drawbar pocket member formed with a drawbar pocket proper and beneath the latter with a pocket to receive the end of a safety bar, and 15 formed also with alined passages through

the walls of said pockets for a drawbar pin, of a drawbar having its ends received in the drawbar pockets of said foot plate and member and having apertures in its ends to receive the drawbar pins, and a safety bar 20 having its ends received in the lower pockets of said foot plate and drawbar pocket member, and having apertures in its ends to receive said drawbar pins, and drawbar pins mounted in said passages and passing 25 through said apertures, and means for retaining the lower portions of the drawbar pins in case of rupture of upper portions of said pins.

HARRY A. HOKE.
